MISSILE NOSE FUZE

William J. Donahue, Jr., Takoma Park, Md., and Lawrence E. Burkhardt, Washington, D. C., assignors to the United States of America as represented by the Secretary of the Navy

Application July 11, 1955, Serial No. 521,428

7 Claims. (Cl. 102—78)

(Granted under Title 35, U. S. Code (1952), sec. 266)

The invention described herein may be manufactured and used by or for the Government of the United States of America for governmental purposes without the payment of any royalties thereon or therefor.

This invention relates to a missile nose fuze of the percussion type having a mechanical delay arming device.

An object of the invention is to provide a new and improved missile fuze which will cause the detonation of the main bursting charge of the missile to occur after a predetermined depth of target penetration.

Another object of the invention is to provide a new and improved missile fuze which includes means to retain the fuze mechanism in an unarmed position until the missile has travelled a predetermined interval after launching or firing thereof.

A further object of the invention is to provide a missile fuze which includes new and improved means for self destruction after a predetermined interval of travel if no target has been encountered by the missile during that interval.

A still further object of the invention is to provide an improved missile fuze, simple in construction and having a minimum number of moving parts, thereby assuring smooth and effective operation of the fuze, and a minimum of mechanical sources of defects.

Other objects of the invention will become apparent from the following description taken in connection with the accompanying drawings wherein:

Fig. 1 is an axial sectional view of the fuze according to one embodiment of this invention showing the fuze mechanism in an unarmed or safety position;

Fig. 2 is a cross sectional view on the line 2—2 of Fig. 1 showing the arming rotor in an unarmed or safety position;

Fig. 3 is an axial sectional view of the fuze showing the fuze mechanism in an armed or firing position;

Fig. 4 is a cross sectional view on the line 4—4 of Fig. 3 showing the arming rotor in the armed or firing position; and

Fig. 5 is a plan view partially broken away and illustrating the escapement mechanism which guides the inertial safety sleeve in a manner to release the fuze mechanism from an initial safe position.

Referring more particularly to the drawings wherein like numerals indicate like parts throughout the several views and more particularly to Fig. 1 whereon is shown an ordnance missile, such as a rocket 1 to which is secured a nose fuze generally indicated by the numeral 2 in any convenient manner but preferably as by threaded engagement therewith. The nose fuze comprises a fuze casing 3 having a cavity 4 axially extending therethrough and annular recesses 57 and 58 formed therein; and within which cavity the entire fuze mechanism is disposed. The fuze mechanism includes a percussion head 5, plastic striker 6, timing washer 7, firing plunger 8, arming rotor 9, detonator 11, booster charge 12, and slideable sleeve system generally indicated by the numeral 10.

The firing plunger 8 comprises a slotted tubular stem

2

51 having a firing pin 52 rearwardly formed by the tapered portion of the stem 51, and having a tapered blade 53 disposed within the slot and secured therein by pin 54.

5 Disposed within a cavity 35 of cylindrical housing 36 is spring 37, lead in 38, and an arming rotor 9 rotatably secured in the cavity by pin 39. Axially disposed within a bore 41 of the arming rotor is detonator 11. The detonator is normally maintained in the safe position shown in Fig. 2 by interposition of stem 42 into recess 49. The withdrawal of stem 42 from recess 49 results in the rotation of the arming rotor by spring 37 thereby aligning the detonator with explosive arming train, or flash channel 25.

15 Axially disposed within cavity 4 is tubular sleeve 13 consisting of a forward tapered portion and a rearward annular flange 15 in abutment with shoulder 14 and having a plurality of apertures 16, 17, and 18, and a V-shaped groove 20 formed thereon. Groove 20 consists of two smooth branches 44 and 45 having a recess 31 formed at the intersection thereof, and a zig zag portion 46 contiguous to branch 44. Conformingly disposed within sleeve 13 is tubular sleeve 19 consisting of a forward tapered portion to which timing washer 7 is secured 20 and a plurality of complementary apertures 61, 62, and 63, formed thereon.

Conformingly encircling sleeve 13 is an inertial sleeve 26 having a port 27 and guide pin 28 formed thereon. Resiliently bearing against the inertial sleeve is compression spring 29, which spring bearing against flange 15 acts as an opposing member to the inertial sleeve. The co-action of guide pin 28 and V-groove 20 provides an escapement mechanism for the proper operation of inertial sleeve 26. The operation of the escapement mechanism is such that upon the action of a sustained thrust greater than the opposing action of spring 29, the inertial sleeve is rotatably displaced rearward following the oscillating movement imposed on the guide pin by the zig zag portion 46 in which the guide pin is initially disposed and the guide pins subsequent run in smooth branch 44 of V-groove 20 toward the vertex of the V-groove whereupon the guide pin becomes seated in recess 31. The seating of the guide pin in the recess arrests the rearward displacement of the inertial sleeve, 45 and upon the cessation of the thrust, the opposing effect of spring 29 again predominates and attempts to force the return of the inertial sleeve to its initial forward position; however the location of recess 31 prevents the return of the guide pin to branch 44 and guides the pin 50 into branch 45 thereby additionally rotating the inertial sleeve as it returns to a forward position. The zig zag portion 46 acts as an acceleration discriminator by allowing only a slight movement of the guide pin initially disposed therein from an inertial force of less magnitude 55 and duration than results from a firing or launching of the missile, i. e. as would result from an accidental dropping of the missile.

The slideable sleeve system, generally indicated by the numeral 10, is axially disposed within sleeve 19 and 60 comprising an outer slide sleeve 21 having apertures 64, 65 and 66 and a forward tapered portion formed thereon, to which portion firing plunger 8 is secured, an intermediate slide sleeve 22 having complementary apertures 67 and 68, and an inner slide sleeve 23 consisting of elongated stem portion 42 and enlarged head portion 43, said head portion having formed therein recesses 55 and 56. Axially disposed within sleeve 23 are primer 24, and flash channel or explosive train 25. Bearing against shoulder 50 of the enlarged head portion 43 and baffle 70 47 is spring 48 tending to impart a forward movement to sleeve 23. Disposed in the complementary recesses throughout the slideable sleeve system are detent, or

locking balls 32, 33, and 34 which lock the slideable sleeve system in an initial telescoped condition and upon displacement from said recesses, by the camming action resulting from the effect of spring 48 on sleeve 23, allow for the timed expansion of the telescoped slideable sleeve system.

The operation of the fuze will now be described.

In safety position, the fuze mechanism is in the position shown in Figs. 1 and 2 wherein the explosive train, or spit channel, from the primer to the booster charge is interrupted by the out of alignment position of the detonator therewith, thereby preventing firing of the fuze by any means.

Upon launching of the missile, and during the period of acceleration, the inertial sleeve is displaced rearward, and upon the cessation of acceleration, is returned to a rotated forward position by the action of spring 29 and the escapement mechanism action previously described. Upon return to a rotated forward position port 27 is aligned with complementary apertures 16, 61, and 64, wherein locking ball 32 is disposed, and by means of the camming action previously described, locking ball 32 is forced outward into recess 57 thereby unlocking the slideable sleeve system from its initial safe telescoped position.

Upon unlocking of the telescoped slideable sleeve system the delay arming period of the fuze is initiated, during which period, the sleeve system begins a unitary forward movement as a result of the action of expansion spring 48 on inner slide sleeve 23 which action is transmitted through the locking balls to the other slide sleeves of the system. The forward movement of the sleeve system is timed, or metered, by the resistance offered by timing washer 7, which is composed of lead, plastic, or other similar material suitable for the purpose, to the shearing effect or intrusion of the tapered blade 53 mounted in firing plunger 8 which is secured to the outer slide sleeve of the sleeve system. Prior to the expiration of this period, contact of the fuze with a target would not detonate the fuze because such contact would jam sleeve 19 against locking ball 34 thereby preventing displacement of detent ball 34 and constraining primer 24 from contact with firing pin 52.

The delay arming period of the fuze continues until the timed forward movement of the sleeve system 10 causes locking ball 34 to register with apertures 63 and 18 whereupon the locking ball is forced outward into recess 58 as shown in Fig. 3 by the previously described camming action. Stem 42 thereupon withdraws from recess 49 of the arming rotor and the rotor is rotated to an armed position as shown in Fig. 4 by spring 37 thereby aligning detonator 11 with the explosive train and rendering it continuous from the primer 24 to the booster charge 12. The fuze is now armed and will fire upon contact with a target by reason of the transmission of the contact impulse through the percussion head 5 and plastic striker 6 to sleeve 19 thereby driving the sleeve aft until aperture 62 registers with apertures 65 and 68 within which locking ball 33 is disposed. Upon registering, locking ball 33 is forced outward into recess 58 by camming action whereupon slide sleeve 23 is driven rapidly forward by expansive spring 48 until primer 24, disposed therein, contacts firing pin 52 and is actuated thereby to fire the fuze.

In the event that no target has been encountered by the fuze during its armed period, which period is predetermined by the rate of penetration of blade 53 into timing washer 7, the slide sleeve system continues its metered forward movement until detent ball 33 registers with aperture 62 and is forced outward into recess 58 by camming action thereupon freeing sleeve 23 to be driven rapidly forward as previously described. The fuze is thus self destructing in the event no target is encountered during its effective trajectory.

Although the time required for the forward travel of sleeve 23 to bring the primer disposed therein into firing contact with the firing pin after contact of the fuze with a target may result in sufficient time delay to cause the desired degree of target penetration before firing of the fuze, it is apparent that a greater degree of target penetration may be effected by the interposition of shearing wire, or washer 59 to sleeve 22 to require shearing thereof.

Obviously many modifications and variations of the present invention are possible in the light of the above teachings. It is therefore to be understood that within the scope of the appended claims the invention may be practiced otherwise than as specifically described.

15 What is claimed as new and desired to be secured by Letters Patent of the United States is:

1. A nose fuze for a missile comprising a fuze casing adapted to be secured to the missile; an arming rotor rotatably supported within said casing in an initially safe position and being rotatable to an armed position; a slideable sleeve system axially supported within said casing in an initially telescoped condition for maintaining said arming rotor in a safe position and for allowing rotation of said rotor to an armed position upon expansion thereof, said system including an inner slide sleeve, an intermediate slide sleeve conformingly encircling said inner slide sleeve, an outer slide sleeve conformingly encircling said intermediate slide sleeve, each of said slide sleeves having a plurality of recesses formed thereon and initially in telescoped relationship with each other, resilient means acting on said slideable sleeve system and tending to expand the telescoped slideable sleeve system, a plurality of detent balls disposed in said recesses for maintaining said system in a telescoped condition until discrete displacement of said detent balls from said recesses, and camming means for displacing said detent balls thereby allowing the expansion of said telescoped system by said resilient means; inertial safety means for locking said system in said initial telescoped condition until the missile is launched; intrusively coacting means for effecting a predetermined metered expansion of said system upon release thereof from said initial telescoped condition; and detonating means for firing said fuze when said arming rotor is in said armed position.
2. A nose fuze according to claim 1, wherein said inertial safety means includes an inertial sleeve slideably encircling said slideable sleeve system and having a port and a guide pin formed thereon, resilient means bearing on said inertial sleeve for maintaining it in an initial forward position, complementary recesses in said sleeve system out of alignment with said port when said inertial sleeve is in said initial forward position, a detent ball disposed in said recesses for locking said sleeve system, an escapement mechanism for allowing rearward movement of said inertial sleeve in response to a predetermined inertial force and for causing return of said inertial sleeve to a rotated forward position thereby to align said port with said recesses, and camming means for displacing said detent ball upon alignment of said port and said recesses thereby to unlock said slideable sleeve system.
3. An escapement mechanism according to claim 2 comprising a V-grooved cam surface formed on said slideable sleeve system, a guide pin on said inertial sleeve coacting with said grooved surface and adapted to run therein, said V-grooved surface having a pair of smooth branches and a zig zag arm contiguous with one of said smooth branches and within which said guide pin is initially disposed, said zig zag branch being adapted to limit rapid movement of said guide pin therein, said guide pin adapted to run rearward through said zig zag arm and one of said smooth branches to the vertex of said V-groove upon subjection of the fuze to an inertial force of a predetermined magnitude and duration thereby to

rotate the inertial sleeve in its rearward movement, a recess formed in said surface at said vertex and so disposed as to guide the guide pin into the second smooth branch of said V-groove upon cessation of said inertial force thereby to additionally rotate said inertial sleeve upon return thereof to said rotated forward position.

4. A nose fuze according to claim 1, wherein said slideable sleeve system further includes a firing member axially secured to said outer slide sleeve and comprising an elongated slotted stem, a tapered blade disposed in said slotted stem, resilient means tending to impart forward movement to said outer slide sleeve, detent means normally opposing the forward movement of said outer slide sleeve, a plurality of fixed sleeves encircling said outer slide sleeve, a washer secured to the forward portion of one of said fixed sleeves in a transverse position and having a bore centrally disposed therethrough and of less diameter than the width of said blade, said washer being in spaced alignment with said firing member and adapted to be cut by said blade and thereby oppose the movement of the blade therethrough, and camming means for displacing said detent means for allowing forward movement of said outer slide sleeve and firing member by said resilient means at a rate determined by the opposition of said washer to said movement of the blade.

5. A delay arming mechanism for an ordnance fuse comprising a fuze casing having a bore axially formed therein, a permeable member transversely secured within the forward portion of said bore, a slideable sleeve system arranged within said bore in a normally locked telescoped condition for maintaining the fuze unarmed, said system being spring biased for expansion in a forwardly direction upon unlocking thereof thereby effecting arming of said fuze, an inertial member slidably encircling said system for effecting locking thereof and in response to a predetermined inertial force for effecting unlocking of said system, and an intrusive member driven by said sleeve system and in operative engagement with said permeable member for effecting a metered expansion of said sleeve system upon unlocking thereof by penetration of said permeable member by said intrusive member.

6. A delay arming and self destruction mechanism for an ordnance fuze comprising a fuze casing having a bore axially formed therein, an arming rotor having a detonator disposed therein and rotatably arranged in said bore in an initially releasably-locked unarmed condition and being rotatable to an armed position upon release thereof, a shearable washer transversely secured within said bore, an arming system arranged in said bore for effecting locking and release of said arming rotor, said system including a plurality of encircling sleeves normally locked in telescoped relationship with each other and being adapted to be expanded into an extended relationship upon unlocking thereof, means including an inertial sleeve and a plurality of detents operatively engaging said system for effecting the locking and discrete unlocking thereof, a primer disposed in one sleeve of said system and being in operational alignment with said detonator

upon release of said rotor, and a firing pin affixed to another sleeve of said system in spaced alignment with said primer and having a cutting edge formed thereon, said pin being adapted to shearably engage said washer upon unlocking of said sleeve system by said means thereby to effect a metered expansion of said system until said pin engages said primer for effecting ignition thereof and of said detonator.

7. An impact responsive ordnance fuze comprising a fuze casing having an axial bore formed therein, an arming rotor having a detonator therein arranged in said bore, said rotor being normally releasably-locked in an unarmed position and being rotatable to an armed position upon release thereof, a stationary sleeve axially arranged within said bore and having a shearable member secured to the forward end thereof, a slideable sleeve system axially arranged within said stationary sleeve, said system including a plurality of conformingly encircling coaxial sleeves normally locked in a telescoped condition for effecting locking of said arming rotor and for rendering the fuze unresponsive to target impact and being expandable for releasing said arming rotor and for rendering said fuze responsive to target impact, system locking means including an inertial sleeve encircling said stationary sleeve and a plurality of detent balls operatively engaging said coaxial, stationary and inertial sleeves for locking said sleeve system in said telescoped condition and for effecting discrete expansion thereof in response to an inertial force of predetermined magnitude, resilient means in operative engagement with one of said coaxial sleeves for effecting a forwardly expansion of said sleeve system upon release thereof, a primer disposed in said one coaxial sleeve in operational spaced relationship with said detonator upon release of said arming rotor, and a firing member affixed to another of said coaxial sleeves in operational spaced alignment with said primer, said firing member having a cutting surface formed thereon for shearably engaging said shearable member upon expansion of said sleeve system thereby effecting a time expansion thereof for rendering said fuze responsive to target impact and for effecting self destruction of said fuze in the absence of target impact by effecting engagement of said firing member with said primer thereby igniting said primer and said detonator.
